US0D1062461S

(12) United States Design Patent (10) Patent No.: US D1,062,461 S
(45) Date of Patent:  Feb. 18, 2025

(54) PACKAGING JAR

(71) Applicant: The Procter & Gamble Company,
Cincinnati, OH (US)
(72) Inventors: U-Ping Loh, Singapore (SG); YunQin
Lee, Singapore (SG)
(73) Assignee: The Procter & Gamble Company,
Cincinnati, OH (US)
() Term: 15 Years
(21) Appl. No.: 29/945,564
(22) Filed: Jun. 4, 2024

(57) CLAIM

The ornamental design for a packaging jar as shown and described.

DESCRIPTION

FIG. 1 is a perspective view of the packaging jar, showing our new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

In the drawings, the broken lines show portions of a packaging jar that form no part of the claimed design.

1 Claim, 2 Drawing Sheets
